UNITED STATES PATENT OFFICE.

JOHN BERNARD BULMER, OF TORONTO, ONTARIO, CANADA.

TRACK-SWITCH.

1,138,624.

Specification of Letters Patent.

Patented May 11, 1915.

Application filed January 16, 1914. Serial No. 812,413.

To all whom it may concern:

Be it known that I, JOHN BERNARD BULMER, of the city of Toronto, in the county of York and Province of Ontario, Canada, have invented certain new and useful Improvements in Track-Switches; and I hereby declare that the following is a full, clear, and exact description of the same.

This invention relates to an automatically-actuated track switch which can be selectively set by corresponding coöperating means attached to a car or train, as herein-after set forth and particularly pointed out in the claims.

In the drawings: Figure 1, is a perspective view of a switch and the switch-operating mechanism; and, Fig. 2, is a similar view, showing a modification of the switch-operating mechanism to that shown in

Fig. 1.

Like characters of reference refer to like parts throughout the specification and drawings.

The switch-operating mechanism consists essentially of a switch box set in the road bed in juxtaposition to the switch *d*, and in which is contained the switch-operating mechanism hereinafter described. This switch-operating mechanism may be generally described as comprising a lever *a* connected with the switch *d* and normally inoperative lever-moving means actuated by corresponding coöperating means attached to the car.

In Fig. 1, the lever *a* is provided with a hub *f* encircling the fulcrum *a'*, and extending from the sides of the hub *f* are lugs *g*. Pivoted to the lugs are L-shaped arms *h*, each of which normally rests on the inner end of a rocker lever *i*. The rocker levers *i* oscillate on their fulcrums *i'* to elevate the arms *h*, so that their L-shaped ends *h'* will project above the surface of the road bed, and to lower them so that the L-shaped ends *h'* will be below the surface of the road bed, as hereinafter described. The outer end of each of the rocker-levers *i* is provided with a presser plate *j* to be engaged by the rims or flanges of the car wheels *j'* as the car wheels pass over it, for the purpose of depressing those ends of the rocker levers and raising the inner ends to elevate the arms *h* and bring their L-shaped ends *h'* above the road bed. Pivoted below the car body are two toggle levers *k* having at their inner ends gripping members *l* to engage with the

L-shaped ends *h'* of the arms *h*. Vertically movable through the car body are plungers *m* engaging the outer ends of the toggle levers *k*, either of which may be held in a lowered position by a pivoted arm *k''* which can be positioned to hold either selected plunger down. The toggle levers *k* are fulcrumed at *k'*, *k''*, and are jointed at *k''*. Bearing against the car bottom and against the toggle levers interjacent the fulcrums *k'*, *k''*, are springs *o* which normally throw the joint *k''* out of line with the fulcrums *k'*, *k''*, and by doing so, raise the gripping members *l* into an inoperative position. When either of the plungers *m* is depressed, it straightens the parts of its respective toggle lever *k* by bringing the joint *k''* into line with the fulcrums *k'*, *k''*, and by doing so, lowers its respective gripping member *l* to engage the L-shaped end *h'* of its respective arm *h*. The engagement of the gripping member *l* with the end *h'* moves that arm *h* in the direction the car is traveling, and causes the oscillation of the lever *a*. For example, the engagement of the gripping member *l* at the right side of the car which is shown in Fig. 1 to be lowered carries the arm *h*, on the right side of the fulcrum *a'*, forward with it and throws the lever *a* and switch *d* to the left, and the engagement of the gripping member *l* at the left side of the car with the arm *h*, at the left side of the fulcrum *a'*, carries that arm forward with it and moves the lever *a* to the right to throw the switch to the right. The L-shaped ends *h'* of the arms *h* are so formed that when the gripping members *l* move the lever *a* to its limit of motion, the gripping members will disengage from the L-shaped ends *h'* and leave the parts in the position to which they have been moved.

In Fig. 2, I have dispensed with the L-shaped arms *h'* and rocker levers *i*, and have connected to the lever *a* adjacent to its fulcrum *a'*, two arms *p* located on opposite sides of the fulcrum, and I have also provided a rock shaft *r* having cam-shaped elements *q* loosely mounted on it to be engaged by rollers *t'* on the ends of the toggle levers *k*. The cam-shaped elements *q* may normally project above the road bed to be engaged by the rollers *t''* when the levers *k* are set by the action of the plungers *m*. The rollers *t'* are normally held by the springs *o*, out of operative relation with the cam-shaped elements *q*, and are brought into op-

erative relation with these elements *q* by the lowering of the plungers *m*. When a roller *l* has been set, it engages its respective cam-shaped element *q* and by bearing down on it, oscillates said element *q* and causes it to move its respective arm and oscillate the lever *a*.

By means of either of the foregoing constructions, I am able to positively set the 10 switch when either of the toggle levers is moved to a position where it will have operative relation with the lever-moving device.

Having thus fully described the nature of 15 my invention, what I claim as new and desire to secure by Letters Patent, is:—

1. The hereinbefore described device comprising a switch, a switch-moving lever con-

nected therewith, two arms pivotally connected with the lever on opposite sides of its 20 fulcrum, and rocker levers to raise said arms.

2. The hereinbefore described device comprising a switch, a switch-moving lever connected therewith, two arms pivotally connected with the lever on opposite sides of its fulcrum, and rocker levers to raise said arms, in combination with adjustable means 25 carried by the car to selectively engage either of said arms and move the lever to 30 predetermine the position of the switch.

Toronto, Ont., Jan. 8th, 1914.

JOHN BERNARD BULMER.

Signed in the presence of—

CHAS. H. RICHES,
F. F. BOOTHBY.
